GRINDING MACHINE FEEDING
MECHANISMHerbert A. Silven, Worcester, Mass., assignor to
Norton Company, Worcester, Mass., a corpora-
tion of Massachusetts

Application May 5, 1933, Serial No. 669,565

6 Claims. (Cl. 51—95)

This invention relates to grinding machines, and more particularly to a hydraulically operated grinding wheel feeding mechanism.

Heretofore, it has been common practice in the grinding field in cylindrical grinding operations to move either the work or the wheel relatively toward and from the other member to produce the desired grinding action and reduce the work piece to the required size. Such feeding movements have been effected by manually controlled feeding mechanisms, as well as power operated mechanisms, such as electrically, mechanically or hydraulically driven mechanisms. To obtain accuracy in regard to size of the finished work piece, as well as quality of finish, it has been desirable to feed the wheel first at a rapid rate until the wheel and work engage each other, then at a slow rate or grinding feed to reduce the work piece to the required size, and then to definitely limit the forward feeding movement of the grinding wheel by a stopping device which holds the wheel and work in a fixed position relative to each other for a finish grinding operation to reduce the work piece to a predetermined size. In previously devised feeding mechanisms, this has been accomplished by power actuated mechanisms which moved the wheel slide to a definite stop, and by manually operated devices, whereby the feed wheel was turned at a rapid rate until the wheel engaged the work, then at a slower rate to produce the desired grinding feed, and finally stopped to allow the wheel and work to remain in grinding contact, with no relative feeding movement between the two members, such as is shown in the patents to Norton Nos. 1,653,922 and 1,416,054.

It is the primary object of this invention to provide a hydraulically actuated wheel feeding mechanism by which the work and wheel may be fed rapidly relatively toward and from each other, first at a rapid rate and then at a slower rate for finish grinding the work piece.

It is another object of this invention to provide a wheel feeding mechanism having a manually rotated feed screw mechanism to permit adjustment of the wheel position, a fluid pressure piston and cylinder to cause a rapid approaching and receding movement between the wheel and work, and a secondary mechanism to modify the approaching movement and produce a slow grinding feed.

It is still another object of this invention to provide a feeding mechanism for moving a wheel slide by means of a fluid pressure system including a piston and cylinder which are arranged to feed the grinding wheel rapidly toward and from

the work, and a secondary self-contained fluid pressure system having a piston arranged in axial alignment with the first named piston and cylinder to modify the movement caused by the first cylinder and produce a slow, uniform grinding feed to finish grind the work.

It is still a further object of this invention to provide a wheel feeding mechanism in which a fluid pressure piston and cylinder are provided to move the wheel slide toward and from the work, and a dash pot piston is slidably mounted on a projecting portion of the piston rod surrounded by a dash pot cylinder which is arranged to modify the feeding movement caused by said piston and cylinder to produce a slow grinding feed.

Other objects will be apparent from the following disclosure. One embodiment of this invention has been illustrated in the drawing, in which like numerals indicate like parts:

Fig. 1 is a fragmentary cross-sectional view through a grinding machine, showing the improved fluid pressure wheel feeding mechanism;

Fig. 2 is a fragmentary sectional view, on an enlarged scale, showing the dash pot mechanism located at the right-hand end of Fig. 1; and

Fig. 3 is a fragmentary cross-sectional view, taken approximately on the line 3—3 of Fig. 2.

This invention comprises a grinding wheel feeding mechanism for causing a relative approaching and receding movement between the grinding wheel and a rotatable work piece, which is arranged so that the wheel feeding movement will take place first at a rapid rate to bring the work and wheel into engagement with each other, then at a slow rate to obtain the desired grinding action between the wheel and work to reduce the work in size, and finally stopping the wheel feed by means of a positive stop and allowing the wheel to spark-out or finish grind the work, during which time there is no relative feeding movement.

A fluid pressure system serves to cause a rapid relative approaching and receding movement between the work support and the grinding wheel, and a secondary self-contained fluid pressure system serves to modify said rapid relative approaching movement and cause a slow uniform grinding feed. An adjustable stop serves to limit the forward feeding movement of the grinding wheel and allows the wheel and work to remain in contact with each other to finish grind the work and to reduce it to a predetermined size.

In the preferred construction, the feeding mechanism comprises a fluid pressure actuated piston in axial alignment with and arranged to move a rotatable feed screw endwise so as to feed

a grinding wheel and a work blank relatively toward each other at a rapid rate. A secondary self-contained fluid pressure system including a dash pot also in axial alignment with the feed screw is effective, after a predetermined rapid feed, to cause a slow feeding movement of the grinding wheel, and an adjustable stop associated with the dash pot positively limits the approaching movement between the grinding wheel and the work feed. The invention is equally applicable to either of the standard types of cylindrical grinding machines, in one of which the work is mounted on a slide movable toward and from the periphery of a stationary grinding wheel, and in the other the rotatable grinding wheel is mounted on a wheel slide arranged for a transverse feeding movement relative to a stationary work support.

As illustrated in the drawing, a grinding machine is provided having a base 10, which is provided with a wheel slide 11 slidable transversely on suitable ways 12. A rotatable grinding wheel 13 is mounted on a wheel spindle 14 which is supported for rotation in suitable bearings (not shown) on wheel slide 11. The grinding wheel may be rotated from any suitable source of power, either by means of a driving belt from an overhead countershaft or, as is the usual case in the modern grinding machine, driven from an electric motor either mounted within the base or on the wheel slide. A work piece 15 is rotatably mounted on a headstock 16 and footstock (not shown) which are in turn supported on a longitudinally movable table 17. The table 17 is supported by a V-way 18 and a flat way 19 on the base 10 and serves to position the work piece relative to the operative face of the grinding wheel.

To produce a relative feeding movement between the grinding wheel 13 and the work piece 15, a suitable feeding mechanism is provided which may comprise a half nut 25 depending from the wheel slide 11 and meshing with a rotatable cross feed screw 26 which is supported in bearings 27 and 28 respectively in the base 10. A manually operable feeding mechanism is provided comprising a manually operable micrometer feed wheel 29, such as that shown in the prior patent to Norton No. 762,838 dated June 14, 1904. Details of the micrometer adjustment of the feed mechanism have been omitted, since they are not part of the present invention. For further reference to detailed construction of the micrometer adjusting device, reference may be had to the above-mentioned patent. The feed wheel 29 is rotatably mounted on a stud 30 which also supports a gear 31 meshing with a gear 32 mounted on the outer end of a rotatable shaft 33. The shaft 33 is supported in bearings 36 and 35 in the base 10, and is slidably keyed by means of a key 37 to a reduced portion 38 of the feed screw 26. It will be readily apparent from the foregoing disclosure that rotation of the manually operable feed wheel 29 transmits motion through gears 31 and 32 and shaft 33 to rotate the cross feed screw 26 and cause a relative approaching or receding movement between the work piece 15 and the grinding wheel 13. The mechanism above described serves to manually adjust the position of the grinding wheel relative to the work piece and may, if desired, be utilized to cause a grinding feed.

In the preferred construction, however, a suitable fluid pressure mechanism is provided which is arranged to move the slide so as to cause either

a rapid approaching or receding movement between the wheel and work, and then also a slow relative approaching movement during the grinding operation. This mechanism may comprise a fluid pressure cylinder 40 supported on the base 10 and having a piston 41 slidably mounted therein in axial alignment with the cross feed screw. The piston 41 is mounted on a piston rod 42 which extends from each end of the piston and projects through the ends of said cylinder. The rod 42 is connected at its outer end to the rear end of the feed screw 26. A cylindrical slidably mounted member 45 is arranged to slide within a cylinder 46 and is slidably keyed thereto by means of a key 47. The slide 45 carries the bearing 28 which in turn supports the rear end of the feed screw 26. The piston rod 42 is operatively connected to move the slide 45.

A fluid pressure system is provided including a reservoir 50 within the base 10 and a pump 51 which pumps fluid through a pipe 52 and a pipe 53 through a reversing valve 54 into the cylinder 40. A suitable relief valve 55 is provided in the pipe line 53 which is arranged so that excess pressure in the system will by-pass fluid through a pipe 56 into the reservoir 50.

The reversing valve 54, of the balanced piston type, is provided with a valve piston 57 which is preferably manually controlled by means of a lever 58 pivotally mounted on a stud 59 and connected by a rod 60 with the valve piston 57. In the position of the valve piston 57, as illustrated in Fig. 1, fluid under pressure is admitted through the reversing valve into a cylinder chamber 61 to move the feed screw 26 bodily toward the left, and cause a rapid approaching movement of the grinding wheel 13 relative to the work piece 15. The parts illustrated in Fig. 1 are shown with the work and wheel in grinding engagement with each other. During the approaching or infeeding movement, fluid is exhausted from a cylinder chamber 61, through the reversing valve 54, a pipe 62, into the reservoir 50.

When it is desired to cause a rearward movement of the grinding wheel slide, the operator moves the manually operable control lever 58 in a clockwise direction, as viewed in Fig. 1, so as to admit fluid under pressure from the pipe 53 into the cylinder chamber 61 to cause an endwise movement of the feed screw 26 toward the right, as viewed in Fig. 1.

Dash pot control

It is desirable to provide a suitable mechanism for reducing the rapid approaching movement to a slow grinding feed when the grinding wheel has been brought into engagement with the work piece. In the preferred construction, a secondary self-contained fluid pressure system is provided which, as illustrated, comprises a dash pot 65 having a dash pot piston 66 arranged in axial alignment with the feed screw and preferably so constructed and arranged that the dash pot piston 66 is slidably mounted on an extended portion 67 of the piston rod 42. When the wheel is fed toward the work, a rapid approaching movement is obtained until a sleeve 68, which surrounds the rod 67, engages the end of the dash pot piston 66 which serves to modify the approaching movement of the grinding wheel so as to reduce the feed to a proper grinding feed. To facilitate adjustment of the sleeve 68 relative to the piston rod portion 67, an internal thread on the sleeve engages a threaded portion 71 on

the rod 67 and may be located in adjusted position by a lock nut 69. A spring 70 within the dash pot piston 66 and surrounding the rod 67 serves to return the dash pot piston to its initial or rearward position during the separating movement between the wheel and work. During the idle return movement of the dash pot piston 66, oil is drawn through a ball check valve 74 into a dash pot chamber 72 from a self-contained reservoir 73 which is formed integral with the dash pot cylinder 65, so that the dash pot is then in condition for the next grinding operation.

The rearward or idle stroke of the dash pot piston 66 under the influence of the spring 70 is limited by a pin 81, fixed to the piston and projecting through the dash pot cylinder head, which engages an adjustable stop nut 82.

When the movement of the piston 41 starts to move the dash pot piston 66 toward the left, as viewed in Fig. 1, the oil escapes slowly from the chamber 72 through a needle valve 75, a port 76 and back to the reservoir 73. The forward grinding feed continues until the adjustable sleeve 80 engages the end of the dash pot cylinder 65, thereby positively limiting the approaching movement between the grinding wheel and the work.

The operation of this mechanism will be readily apparent from the foregoing disclosure. The operator places the desired piece of work in the machine and moves the control lever 58 into the position as illustrated in Fig. 1 to cause a rapid approaching movement of the grinding wheel toward the work piece. This approaching movement of the wheel toward the work continues until the sleeve 80 engages the dash pot piston 66 which, as previously described, serves to modify the rapid approaching movement of the grinding wheel so as to produce a slow grinding feed until the adjustable sleeve 80 engages the fixed stop surface on the end of dash pot cylinder 65. This allows the grinding wheel to remain in grinding engagement with the work to finish grind the same. By manipulation of the adjustable stop sleeve 80 and the needle valve 75, the stopping of the infeed and the rate of the grinding infeed may be regulated. By utilizing the manually operable feed wheel 29, the grinding wheel 20 may be manually positioned relative to the fluid pressure system in setting up the machine for a given operation.

Having thus described the invention, what is claimed as new and desired to be secured by Letters Patent is:

55 1. A grinding machine comprising a base having a work support and a rotatable grinding wheel thereon, a transversely movable wheel slide for moving said wheel toward and from the work, a fluid pressure system including a piston and cylinder interposed between the base and wheel slide and arranged to cause a transverse movement of said slide, a piston rod operatively connected to move the slide and cause a rapid approaching and receding movement between the wheel and work, and a secondary fluid pressure system including a dash pot piston slidably mounted on said piston rod, a dash pot cylinder surrounding said dash pot piston and fixed to the end of said first cylinder and an adjustable stop carried by said rod which is arranged to engage and move said dash pot piston so as to modify the feeding movement of the slide caused by the first named piston and produce a slow grinding feed.

75 2. A grinding machine comprising a base hav-

ing a work support and a rotatable grinding wheel thereon, a transversely movable wheel slide for moving said wheel toward and from the work, a manually rotatable screw rotatably supported in said base and operatively connected to move the slide, a fluid pressure system including a piston and cylinder interposed between the base and slide, a piston rod operatively connected and arranged in axial alignment with said feed screw, non-rotatable connections between said piston rod and screw to move the screw bodily endwise and cause a rapid approaching and receding movement between the wheel and work, and a secondary fluid pressure system including a dash pot piston slidably mounted on said piston rod, a dash pot cylinder surrounding said dash pot piston and fixed to the end of said first cylinder which is arranged to modify the feeding movement of the slide caused by the first named piston and produce a slow grinding feed.

3. In a grinding machine, a feeding mechanism for a grinding wheel comprising a base, a movable wheel slide, a fluid pressure system including a cylinder fixed to the base, a piston slidably mounted within said cylinder, a double end piston rod extending through opposite ends of said cylinder, connections between one end of said piston rod and the slide to move the slide and cause a rapid approaching and receding movement of the wheel, a secondary fluid pressure system including a piston slidably mounted on the other end of said piston rod, a dash pot cylinder surrounding said second piston and fixedly mounted on said first cylinder, a valve arranged to regulate the exhaust of fluid from said dash pot cylinder, and an adjustable member on said piston rod arranged to engage and move the dash pot piston so as to modify the feeding movement of the slide caused by the first piston and cause a slow grinding feed.

4. In a grinding machine, a feeding mechanism for a grinding wheel comprising a movable wheel slide, a nut and screw mechanism arranged to move the slide, a fluid pressure system including a cylinder fixed to the base, a piston slidably mounted within said cylinder, a double end piston rod extending through opposite ends of said cylinder, non-rotatable connections between one end of said piston rod and the feed screw operatively connected to the feed screw to move the screw endwise and cause a rapid approaching and receding movement of the wheel, a secondary fluid pressure system including a piston slidably mounted on the other end of said piston rod, a dash pot cylinder surrounding said second piston and fixedly mounted on said first cylinder, a valve arranged to regulate the exhaust of fluid from said dash pot cylinder, and an adjustable member on said piston rod arranged to engage and move the dash pot piston so as to modify the feeding movement of the slide caused by the first piston and cause a slow grinding feed.

5. In a grinding machine, a feeding mechanism for a grinding wheel comprising a base, a movable wheel slide, a fluid pressure system including a cylinder, mounted on said base, a piston movable within said cylinder, a piston rod extending from each end of said piston and projecting through the ends of said cylinder, connections between one end of said piston rod and the slide to move the slide and transmit an approaching or receding movement to the grinding wheel slide, a secondary fluid pressure system including a dash pot piston slidably mounted on the other end of said piston rod, a dash pot cylinder 75

surrounding said piston and fixed to the end of said first cylinder, a self-contained reservoir integral with said dash pot cylinder and arranged to supply fluid to said cylinder, a check valve arranged to allow fluid to pass rapidly into the dash pot chamber when the dash pot piston moves rearwardly, a valve effective when the dash pot piston moves forward to regulate the exhaust of fluid from the dash pot chamber, and an adjustable member mounted on said piston rod and arranged to engage the dash pot piston at a predetermined time in the forward feeding movement of the slide to move the dash pot piston and thereby modify the feeding movement caused by the first named piston and produce a slow grinding feed.

6. In a grinding machine, a feeding mechanism for a grinding wheel comprising a half nut and a rotatable feed screw, a fluid pressure system including a cylinder, a piston movable within said cylinder, a piston rod extending from each end of said piston and projecting through the ends of said cylinder, connections between one end of

said piston rod and the feed screw which are arranged to move the feed screw and transmit an approaching or receding movement to the grinding wheel slide, a secondary fluid pressure system including a dash pot piston slidably mounted on the other end of said piston rod, a dash pot cylinder surrounding said piston and fixed to the end of said first cylinder, a self-contained reservoir integral with said dash pot cylinder and arranged to supply fluid to said cylinder, a check valve arranged to allow fluid to pass rapidly into the dash pot chamber when the dash pot piston moves rearwardly, a valve effective when the dash pot piston moves forward to regulate the exhaust of fluid from the dash pot chamber, and an adjustable sleeve mounted on said piston rod and arranged to engage the dash pot piston at a predetermined time in the forward feeding movement of the slide to move the dash pot piston and thereby modify the feeding movement caused by the first named piston and produce a slow grinding feed.

HERBERT A. SILVEN.
